UNITED STATES PATENT OFFICE.

JOSHUA CONN, OF DUNKIRK, NEW YORK, ASSIGNOR TO REUBEN W. WRIGHT, OF DUNKIRK, NEW YORK.

TUBULAR METAL CRUTCH.

SPECIFICATION forming part of Letters Patent No. 724,382, dated March 31, 1903.

Application filed June 20, 1902. Serial No. 112,408. (No model.)

To all whom it may concern:

Be it known that I, JOSHUA CONN, a citizen of the United States, residing at Dunkirk, in the county of Chautauqua and State of New York, have invented certain new and useful Improvements in Tubular Metal Crutches, of which the following is a specification.

This invention relates to a tubular metal crutch; and the object of the invention is to lighten, strengthen, and cheapen the construction and also materially increase the durability of the crutch.

One of the features has reference to the construction of the crutch-body from a single tube which is bent to form the arm part and also the supporting-stem, whereby the body is of one integral tube, thereby dispensing with the brazing of different parts and also lessening the weight and strengthening the same.

This invention also relates to certain details of construction, all of which will be fully and clearly hereinafter described and claimed, reference being had to the accompanying drawings, in which a preferred adaptation of the invention is shown.

Figure 1 is a side elevation of the tubular metal crutch. Fig. 2 is an enlarged detached section through the spring-incasing tube on line *a a*, Fig. 1. Fig. 3 is an enlarged fragmentary section on line *a a*, Fig. 1. Fig. 4 is a detached plan view of the locking-collar. Fig. 5 is an enlarged detached bottom view of the block. Fig. 6 is an enlarged detached central vertical section through the rubber cushion.

In referring to the drawings for the details of construction like numerals designate like parts.

The crutch-body is preferably formed of a light grade of seamless steel tubing, such as used in bicycle construction. In the preferred adaptation shown one piece of tubing is bent at the top to form the concaved arm part 1, and two side portions or members 2 and 3 extend downward from said arm part and are slit and brazed together near their lower ends to form the single tubular lower part 4. A suitable transverse tube 5 is brazed in place between the side portions to constitute a hand-grasp. The lower extremity of

the part 4 is tapered and exteriorly screw-threaded, as shown at 6, and is provided with one or more slots 7. A tube 8, in which a spiral spring 9 is incased, is telescoped in the part 4. The tube 8 is moved longitudinally in the part 4 to lengthen or shorten the crutch and is locked in its adjusted position by tightening a screw-collar 10 on the screw-threaded slotted extremity 6. The upper extreme of the tube 8 is internally screw-threaded, and a tubular screw-plug 11 is screwed into said extreme, against which the upper end of the spring 9 abuts, and the tension of said spring is varied by the longitudinal adjustment of the plug, said plug having one or more depressions 12 in its top edge for the reception of a turning implement. A rod 13, which may be hollow or tubular, if desired to lighten the construction, extends longitudinally within the spring and has its lower end screwed into a lower tube 14, the upper end of which engages against the lower end of said spring. This tube 14 is attached to the lower end of the rod 13 and has two substantially opposite longitudinal slots 15, into which the inner ends of screws 16 extend. The screws 16 pass through the enlarged lower end 17 of the tube 8. (See Fig. 2.) A block 18 is adjustably and detachably secured to the lower end of the tube 14, said block having a vertical internally-screw-threaded opening 19, which screws on the screw-threaded lower end of the tube 14 and is held in its desired position by a lock-nut 20. The opening 19 enlarges at or near the middle portion of the block to constitute a depression or recess 21, and the walls of said recess are provided with an inwardly-extending shoulder or rib 22. A rubber cushion 23 is adapted to be sprung into the recess 21 and has a groove or depression 24, in which the shoulder or rib 22 seats. A spur 25 is also preferably screwed into the lower end of the tube 14 and has a sharpened lower end which is adapted to project through an opening 26 in the cushion 23 when the block 18 is screwed up sufficiently high on the tube 14.

The block 18 and cushion 23 may be attached, if desired, directly to the lower end of the tube 8, thereby dispensing with the spring. 10c

The principal advantages of the invention reside in the increased strength and dura-

bility secured with a lighter and cheaper construction and the rigidity of the crutch against lateral or side strain, which is chiefly owing to the integral construction of the body.

5 I claim as my invention—

1. A crutch-body of a single piece of tubing bent to the desired form and having an arm part and a supporting - stem integral therewith.
- 10 2. A crutch having a body of tubing and comprising an arm part, and two side members integral with and extending downward from said arm part and jointed together near their lower ends.
- 15 3. A crutch having a body of tubing comprising an arm part, two side members integral with and extending downward from said arm part and jointed together near their lower ends and a transverse tube extending between the side members and constituting a hand-grasp.

4. A crutch having a tubular part, a tube telescoping in said tubular part, a spring in said tube, a rod tensioned by the spring, a second tube fastened to the lower end of the 25 rod with its upper portion extending into the lower portion of the first-mentioned tube and having a longitudinal slot, and a screw or similar device extending through the first-mentioned tube and into the longitudinal slot, 30 substantially as set forth.

5. A tubular metal crutch having a tubular lower portion which is tapered screw-threaded and slotted, a tube telescoping in said lower portion and longitudinally adjustable therein 35 to lengthen or shorten the crutch, and a locking screw-collar on said lower portion, substantially as set forth.

JOSHUA CONN.
